UNITED STATES PATENT OFFICE.

CHARLES E. DUNHAM, OF LOS ANGELES, CALIFORNIA.

WASTE-PIPE TOOL.

Application filed April 5, 1926. Serial No. 99,868.

The object of this invention is to provide a convenient and sanitary tool for use in connection with either pop-up or standing waste-pipes and the like used in plumbing, 5 as in wash-bowls, sinks, and the like, for draining the same.

Heretofore no satisfactory means has existed in the plumbing business for holding or turning waste-pipes while the same are 10 being installed, repaired, or removed.

This invention consists of a very small tool that can be carried in the pocket or kit and which can be inserted into the upper 15 ends of waste-pipes quickly, for the purposes above designated; and it consists broadly of a body portion and a plurality of extensions therefrom adapted to engage the waste-pipe for holding, turning, or removing it as stated.

20 The full nature of the invention will be understood from the accompanying drawings and following description and claims.

In the drawings:

25 Fig. 1 is a central vertical section through a wash-bowl and associated apparatus with a pop-up waste-pipe and a waste-pipe tool inserted in the upper end thereof for use, parts being broken away; Fig. 2 is a vertical section of a portion of Fig. 1 on the 30 line 2—2; Fig. 3 is a central section on an enlarged scale of the tool, waste-pipe, and bowl shown in Fig. 1, parts being broken away; Fig. 4 is a section of a wash-bowl similar to that shown in Fig. 1, but with a 35 standing waste-pipe and with a waste-pipe tool applied thereto; Fig. 5 is a section on a large scale on the line 5—5 of Fig. 4; and Fig. 6 is a horizontal section on the line 6—6 of Fig. 5.

40 There is shown herein a washbowl 10 with waste outlet that has in it a pop-up waste-pipe 11, and the bowl has an overflow conduit 12. The overflow conduit provides a second double wall 13 in the bottom of the 45 bowl, as shown in Figs. 1 and 3, and therefore the waste-pipe 11 has two lateral openings 14 for the overflow so that said waste-pipe is skeleton in form. The upper end of the wastepipe has a rim to fit smoothly in the 50 bottom of the bowl, and the lower part is threaded to receive a clamp nut 15 and packing 16 for securing the pipe in place so it will not leak. The foregoing is a common 55 type of construction and the invention is not limited to any particular form of the bowl, sink, or the like.

The waste-pipe 11 is about 3" long and connects with a drain pipe 17. The waste-pipe is provided with a stopper, not shown, that is operated by the stopper operating 60 means 18 and knob 19, all of which is a common construction.

The drain-pipe tool which constitutes this invention consists of a body portion 20, usually two or three inches in length and 65 rectangular, but not necessarily so, and provided with a hole 21 through the upper portion for the insertion of a rod or tool 22 for turning it or resisting its rotation.

The body of the tool is slotted from a 70 point below the hole 21 entirely down to the lower end and widthwise of the tool so as to form a slot or chamber 23 in which there is mounted a pair of fingers or grippers 24, 75 as seen in Fig. 5. Each finger or gripper 24 is pivoted in the holder by a pin 25 near its upper end, and the fingers are located opposite to each other in the slot 23 and taper downwardly somewhat and have their free 80 ends extended beyond the lower end of the body 20. These fingers are spread apart yieldingly by a wire spring 26 that is located between the upper ends of the fingers in A-shaped form and its two lower ends are bent laterally and project into small holes or recesses 27 in the inner walls of the fingers. The tendency of the spring is to force the 85 lower ends of the fingers outward, but such outward movement of the lower ends of the fingers is limited by the rectangular upper outer corner of each finger engaging and abutting against the upper wall 28 of the slot 23.

90 There is a laterally extending ear or projection 30 on the outer edge of each finger towards the lower end thereof but spaced from the lower end of the finger between one-fourth and one-half of an inch, and the ears or projections 30 extend laterally beyond the body of the finger from one-fourth to one-half an inch, although the invention 95 is not limited to these exact measurements. The ears 30 are remote from the free ends of the fingers and inclined in a direction 100 away from the ends of the fingers and toward the body of the tool, and their lower edges are conterminous with the lower end of the body 20.

105 There is shown in Fig. 4 a modified form of bowl 35 and a standing waste-pipe 36. This bowl has no overflow conduit and therefore the bottom is a single thickness. The

upper end of the waste-pipe 36 has a rim so that the pipe can be clamped in place in the bowl by the nut 37, and the lower end of the waste-pipe is connected with a drain pipe 38 controlled by a valve, not shown, at the lower end of the valve stem 39 and operated by a knob 40. This construction is a common type and familiar to all skilled in the art. The waste-pipe 36 is partially closed at its upper end, being provided with a series of holes 41 through which the water drains from the bowl when the valve below is opened.

There are shown herein, therefore, two common types of waste-pipes and a waste-pipe tool adapted to be readily applied to these pipes. In applying the tool to the waste-pipe shown in Figs. 1 to 3, the end of the tool carrying the fingers is inserted down into the pop-up waste-pipe by compressing the ears or projections 30 until after said ears or projections have passed below the upper portion of the waste-pipe, and then they will spring out into the lateral openings 14 of the waste-pipe and engage the walls at the sides of said openings 14 and thus enable the tool to turn the waste-pipe or prevent it from turning.

The waste-pipe can thus be held from turning while the clamp nut 15 is being tightened up or unscrewed. Also the tool can turn the drain pipe for screwing or unscrewing into connection with any part below the bowl.

In the standing waste-pipe 36 shown in Fig. 5, the lower ends of the fingers can be inserted in a plurality of holes 41 in the waste-pipe, and thereby that form of waste-pipe may be held from turning while the nut 37 is being tightened up or released, or the waste-pipe can be turned in one direction or the other if necessary in installing it or removing it.

The tool can be readily withdrawn from the waste-pipe 11 because the upper edges of the projections 30 are inclined as best shown in Fig. 3, and as the tool is withdrawn upward the fingers will automatically be collapsed and thus enable the tool to be removed without injury to the waste-pipe.

The ears 30 are substantially horizontal at their lower ends to serve as stops to limit the downward movement of the tool when inserted in a pop-up waste-pipe 11, as the ears spring into the openings 14 and the lower edges of the ears rest upon the bottom walls of the openings 14. With the standard pipe 36, the free ends of the fingers function to prevent the pipe from turning and both or either of the ears 30 or the lower end of the body 20 serve as a stop, by engaging with the top of the waste-pipe.

This tool enables one to use it for the purpose above explained without injuring, scratching, or marring the waste-pipe or plumbing, thus avoiding great injury to the waste-pipe and plumbing arising from the employment of miscellaneous tools for said purpose.

I claim as my invention:

1. A waste-pipe tool consisting of a body transversely slotted at one end, a pair of oppositely located fingers in said slot which are pivoted near their upper ends to the body, and there being a laterally projecting ear on each finger with the lower end thereof substantially conterminous with the bottom of the body and with the upper edge of each ear inclined upwardly and inwardly, and a spring between said fingers for normally forcing them away from each other.

2. A waste-pipe tool consisting of a body transversely slotted at one end, a pair of oppositely located fingers in said slot which are pivoted near their inner ends with their free ends extending beyond the body of the tool, the inner ends of the fingers and adjacent wall of the slot being arranged to limit the outward movement of the free ends of the fingers, and a spring between said fingers tending to force them laterally outward, each of said fingers having an outwardly projecting ear spaced from the free end of the finger, and the edge of each ear which is remote from the free end of the finger being inclined away from the free end of the finger and toward the body of the tool.

In witness whereof, I have hereunto affixed my signature.

CHARLES E. DUNHAM.
